UNITED STATES PATENT OFFICE.

RICHARD PEALE, OF ST. BENEDICT, PENNSYLVANIA, ASSIGNEE TO REMBRANDT PEALE, OF ST. BENEDICT, PENNSYLVANIA.

MINING MACHINE.

Application filed March 24, 1921. Serial No. 454,986.

To all whom it may concern:

Be it known that I, RICHARD PEALE, a citizen of the United States, residing at St. Benedict, in the county of Cambria and 5 State of Pennsylvania, have made certain new and useful Improvements in Mining Machines, of which the following is a specification.

The invention relates to mining machines, 10 and more particularly to mining machines adapted to cut a kerf about a body of coal on all sides and to convey away the detached coal; and to such special features of invention in such machines as are hereinafter 15 pointed out.

Objects and advantages of the invention will be set forth in part hereinafter and in part will be obvious herefrom, or may be learned by practice with the invention, the 20 same being realized and attained by means of the instrumentalities and combinations pointed out in the appended claims.

The invention consists in the novel parts, 25 constructions, arrangements, combinations and improvements herein shown and described.

The accompanying drawings, referred to herein and constituting a part hereof, illustrate one embodiment of the invention, and 30 together with the description, serve to explain the principles of the invention.

Of the drawings:

Fig. 1 is a top plan of a machine embodying the invention;

Fig. 2 is a vertical section taken substantially on line 2—2 of Fig. 1;

Fig. 3 is a vertical section taken substantially on line 3—3 of Fig. 1;

Fig. 4 is an end elevation, looking at Figs. 40 1, 2 and 3 from the right;

Fig. 5 is an enlarged, fragmentary, detail of the kerf cutting chain and the driving chain therefor;

Fig. 6 is a sectional, fragmentary detail, 45 taken on line 6—6 of Fig. 5;

Fig. 7 is an enlarged, transverse section, taken substantially on line 7—7 of Fig. 4, showing one of the guiding sprockets for the chain which drives the cutter chain;

Fig. 8 is an enlarged transverse section, 50 taken substantially on line 8—8 of Fig. 4, showing the engagement of the driving chain with the cutter chain;

Fig. 9 is an enlarged, transverse section, 55 taken substantially on line 9—9 of Fig. 4,

showing the cutter chain traveling in the bottom reach of its guide;

Fig. 10 is an enlarged, transverse section, taken substantially on line 10—10 of Fig. 4, showing the cutter chain traveling in the 60 upper reach of its guide;

Fig. 11 is an enlarged detail plan view of the automatic clutch mechanism for reversing the direction of travel of the conveyor blades, and showing a detail or modification 65 for preventing the clutch stopping in neutral position;

Fig. 12 is a fragmentary, detached detail, partly in elevation and partly in section of the conveyor blade mechanism, showing a 70 conveyor blade in conveying position;

Fig. 13 is a view corresponding to Fig. 12, but showing a conveyor blade traveling in the return or idle direction;

Fig. 14 is a fragmentary, perspective of a 75 part of the conveyor mechanism, showing the connections between a conveyor blade and its operating chain;

Fig. 15 is a diagrammatic showing of the machine employed in heading or entry work; 80

Fig. 16 is a fragmentary plan, corresponding to the top part of Fig. 1, and showing a baffle plate structure substituted for the short cross conveyor;

Figs. 17, 18 and 19 are details, similar to 85 Figs. 12, 13 and 14, but showing the pusher blade arms adapted to pass the holding down rollers for the sprocket chains.

The invention, in some of the main features of the present exemplified embodiment, 90 comprises a machine frame having a vertically disposed endless or loop cutter chain guideway with the cutter chain running therein, adapted to cut out a core of coal, the guideway being in fixed position on the machine frame and being pressed to the work by the travel of the machine. The cutter chain guideway is arranged across the front of the machine, and is of the full width of the machine frame or just slightly wider 95 than the frame, so that the machine may travel forward and thereby press the cutter chain into the coal, the machine in traveling; cutting space for itself to advance continuously as in entry or heading work.

The space within the cutter chain guideway is entirely clear, so that a kerf is cut by the one cutter chain completely around a core of coal, which core extends over the bottom part of the machine frame, the core 100 110

gradually breaking off and dropping down, due to its weight and the natural cleavage planes in the coal, upon a conveyor disposed horizontally on the machine frame and extending into the horizontal bottom kerf.

The construction is such that a very narrow kerf only need be cut, which greatly reduces the work necessary in cutting out a core of any given size, and renders possible a machine of very light construction, which conduces to ease of handling. In this connection, and conducing to the light and powerful construction of the machine, frame braces are located between the vertical reaches of the transversely disposed cutter chain guideway back to the horizontal frame, these braces entering the kerf behind the vertical reaches of the cutter chain guideway.

Driving means for the cutter chain are provided which are of great general efficiency and likewise conduce to the structural features already referred to, including the narrow kerf cutting mechanism. The cutter chain driving means comprises a motor at the back of the machine and a chain driven thereby and extending to the cutter chain and running along within one of the reaches of the cutter chain guideway and in mesh or engagement with the cutter chain.

The conveyor mechanism provided in the exemplified embodiment also conduces to the light, strong and compact construction of the machine, and will pass into the very narrow horizontal bottom kerf cut by the machine, so as to receive the broken coal as it falls from the core. This conveyor, as embodied, comprises one or more pusher blades, pivotally mounted at the ends thereof on reciprocating chains, the pusher blades lying down when not in use and also when traveling idly backwardly through the coal, but standing up and pushing the broken coal before them during the forward or conveying movement.

Other features of the invention will be set forth hereinafter in connection with the detailed description of the present embodiment, and it will be understood that the foregoing and following description of the various features of the invention are illustrative and exemplary and are not restrictive of the invention.

Referring now in detail to the embodied form of the invention, the machine has a low, flat frame 1 adapted to carry at the front end thereof and in fixed position thereon, the endless kerf cutter which is located on the front of the machine, cutting a very narrow kerf entirely about a core of coal or other mineral, also to support a conveyor mechanism which when idle lies flat and thin and is adapted to enter the thin or narrow kerf beneath the core. The frame 1 also supports at the rear or outer end there-

of a motor for driving the cutter chain and the conveyor, and for advancing the machine to press the front cutter into the work. The machine frame 1 comprises a solid or apertured floor 2, which cooperates with or serves as a part of the conveyor mechanism, as will be hereinafter described.

The kerf cutting mechanism at the forward end of the frame comprises the endless guideway, or guiding frame 5 for the endless cutter chain. This guideway is preferably of substantially rectangular form, having horizontal top and bottom reaches 6 and 7, and connecting vertical reaches 8 and 9 at the two sides, the corners being rounded to permit the cutter chain to make the turns. The lower reach 7 of the cutter chain guideway is integral with or is fixed firmly to the bed plate 2 of the machine frame to support and position the cutting mechanism on the frame.

The cutter frame 5 extends entirely across the full width of the machine frame 1, or is just a trifle wider, so as to provide clearance whereby the machine will advance into the work as the cutter chain cuts its endless kerf, adapting the machine for entry or heading work. It will do room and long-wall work as well. The embodied machine is designed to cut a relatively narrow kerf, thus greatly reducing the amount of work necessary in advancing the machine a given distance, that is, in cutting out a core of coal or other mineral of a given size. For this reason also, the chain cutter can be run at greater speed, and thus a given amount of work or core cutting may be accomplished in a much less period of time. With a small size cutter chain, the cutter guideway mechanism may be reduced in size and lightened, the amount of power required is reduced, and a smaller motor may be used, and the machine throughout made much lighter without reducing or impairing its capacity for work.

In the embodied form and conducing to the lightness of structure just described, while maintaining required strength and rigidity, braces 10 and 11 are provided at either side of the machine, their forward ends being riveted, bolted or otherwise fastened to the vertical reaches 8 and 9 of the endless cutter chain guideway 5, and their rear ends being fastened in like manner to the machine frame. Cross braces 12 may also be provided between the braces 10 and 11. These braces are of a width such as will permit them to pass into the vertical part of the kerf as the machine advances with the cutting of the kerf, and they hold the cutter chain guideway firmly in position, and prevent any springing or backward bending thereof from the pressure exerted thereon while the machine is advancing and the kerf is being cut.

The embodied form of cutter chain is

adapted by structure to cut a narrow kerf and at the same time is of sufficient strength to stand up to the work. The embodied form of cutter chain is likewise adapted to 5 cooperate with and to be driven by a driving chain which meshes with or engages with the cutter chain, running therewith in one of the reaches of the guideway 5. This gives a very powerful and efficient driving means, 10 and also conduces to keep the entire space within the cutter chain guideway free for the projection of the core of coal or other mineral thereinto.

As embodied (Figs. 5 to 10) the cutter 15 chain is provided with links 18 carrying hubs or bosses 19, in which are mounted the cutter teeth 20. Between the links 18 and connected thereto at each end by pivots 21 and 22 are links 23. The links are prefer- 20 ably provided with curved sides which contact with the guideway wall (Fig. 5). The pivots 21 and 22 pass through spacing blocks 25, abutting on the rear face of the links 23. In Fig. 6 and following, the links 23 25 and the spacing blocks 25 are shown integral, the pivots 21 and 22 passing through each block 25. At the rear end thereof, the members 25 are pivotally connected together by links 26, making a continuous link 30 structure at the front and back of the chain.

The cutter chain guideway comprises plates 27 and 28, preferably of rectangular section, as shown in Figs. 7 to 10, the cutter 35 chain fitting therein and running with a free sliding fit. The members 27 and 28 are fastened together in a suitable manner, as by flanges 29 and 30, facing and in contact with one another and fastened together by suitable means such as bolts 31.

40 The embodied form of driving means for the kerf cutter chain comprises a driving chain therefor running within the cutter chain guideway 5 along one of its reaches, and preferably along one of the vertical 45 reaches of the cutter chain, the driving chain engaging with or meshing with the cutter chain (see especially Figs. 2, 5, 6, 7 and 8). As embodied, the links 18 overlie the driving chain and are provided with faces 35, prefer- 50 ably closely adjacent to the cutter teeth 20, with which faces projections or lugs 37 on the driving chain engage. The driving chain comprises links 36, and projecting therefrom are the lugs 37 which engage with

55 the faces 35 of links 18, as shown in Figs. 5 to 8. The driving chain is provided also with connected pivoted links 38 and 39 between the links 36. The links 36 are prefer- 60 ably spaced apart so that a lug 37 engages a link 18 closely adjacent to each cutter tooth 20.

In the embodied form, the driving chain 65 engages with the cutter chain during a large part of the vertical reach 9 of the cutter chain guideway 5. The driving chain runs

within the guideway, alongside the blocks or members 25, and beneath or back of the links 18 of the cutter chain. A bearing strip or bearing blocks 40 may be provided within the guideway 5 back of the driving chain to hold 70 it to engagement with the cutter chain. The preferred manner of driving the driving chain will be later described. Spacing bars 42 in pairs are provided within the guideway 5 in the parts of the guideway in which the driving chain does not run to hold the cutter 75 chain to position, (see Figs. 9 and 10). A spacing bar 42 may be employed in that part of the guideway where the driving chain runs, to keep the rear end of the cutter chain 80 in proper position. The cutter chain is guided into and out of the guideway 5 by suitable means such as sprocket wheels 44, journaled on bearings 45 supported on the wall of the guideway 5.

In the embodied form of driving means for the driving chain, a motor 50 is mounted at the rear end and preferably at one side of the frame 1, that is, in or near one corner of the frame. This motor 50 drives the driv- 90 ing chain, the conveyor, and also the means for advancing the machine to the work, by mechanism which will be later described.

In the embodied form of means for driv- 95 ing the driving chain for the cutter chain, fixed on shaft 51 of motor 50 is a worm 52, which worm meshes with a worm wheel 53 fixed on a shaft 54. Mounted loosely on shaft 54 is a sprocket wheel 55 fixed to which is a clutch member 56. Rotatable with but 100 slidable along shaft 54 is a cooperating clutch member 57, thrown in and out by a suitable hand lever, not shown. By means of the clutch members 56 and 57, the sprocket wheel 55 may be driven from shaft 54 or 105 left at rest. The driving chain for the cutter chain runs over the sprocket wheel 55, the links 38 serving as sprocket links. The driving chain also runs over the idler 110 sprocket wheels 44, already described. Thus the cutter chain is driven from the motor 50, under the control of the clutch 56, 57, which provides for starting and stopping the cutter chain as desired or as may be required or necessary. This mechanism, the 115 motor and the conveyor driving mechanism are preferably protected by a cover or housing 59.

The embodied form of conveyor comprises 120 a plurality of pusher blades 70 reciprocated to and fro over a floor 60, which is just above the bottom or floor 2 of the machine frame 1. These blades lie flat upon the floor 60, when not in use, and also when moving back- 125 wardly on the idle stroke, but they automatically rise into vertical position on the forward or conveying stroke to push the dislodged and broken coal before them toward the rear of the machine. In Fig. 1 a short cross conveyor is shown between the cutter 130

chain guideway 5 and the housing 59, while in Fig. 16, an obliquely positioned baffle plate 61 is employed to push the dislodged coal or other mineral over into the path of the main conveyor.

Referring now in detail to the construction of the conveyor, two reciprocating sprocket chains 63 and 64 run, respectively, over idle sprocket wheels 65 and 66, and 67 and 68 at either end thereof, the pair of chains running from just behind the cutter chain guideway 5 to the rear end of the machine. A plate 62 is preferably employed to direct the coal which is pushed across by the short conveyor or by the baffle plate over rather than against the chain 64.

The pusher blades 70 extend across the conveyor mechanism, and are preferably several in number and are pivotally connected at one end to the chain 63 and at the opposite end to the chain 64, the conveyor or pusher blades 70 occupying nearly the full width of the machine except for the part occupied by the housing 59 for the motor 50 and the driving mechanisms cooperating therewith.

The conveyor blades 70 (Figs. 12, 13 and 14) are connected to their operating chains 63 and 64 so as to operate in the manner already described, that is, the blades 70 lie down flat on the floor 60 when the kerf is being cut and the conveyor is passing into the kerf (as shown in Fig. 14), and they also lie down flat during the operation of the conveyor mechanism when sliding back idly beneath the coal (as shown in Fig. 13), but they automatically rise to vertical position to push the broken and dislodged coal before them in their advancing or conveying movement when they are conveying the coal toward the rear of the machine (as shown in Fig. 12). The blades 70 are placed preferably somewhat closer together than the length of the reciprocatory travel of the chains 63 and 64 so that each blade will gather all the coal left by the blade behind it on the preceding stroke.

As embodied, the blades 70 have pivotal connections 71 at their ends with the chains 63 and 64, respectively. Pivoted to each of the chains 63 and 64 by pivots 72 are arms 73, having slots 74 formed therein. Fixed to the ends of the blades 70 are brackets 75, each terminating in a pin 76 projecting through and slidable in the corresponding slot 74. The blades 70 are provided at their top end with curved fingers 77. The pusher blades 70 may be higher than the side frames of the machine if desired.

As the chains 63 and 64 move backwardly in their idle reciprocatory movement, the blades 70 will fold down into the position shown in Figs. 13 and 14, but when the chains travel in the opposite direction, the fingers 77 will cause the blades 70 to

swing upwardly into vertical position, and they are held in this position during the advancing or conveying reciprocatory movement of the chains 63 and 64 by the pin 76 being in the end of the slot 74.

The embodied form of driving and guiding means for the chains 63 and 64 include the end sprocket wheels 65-68 already referred to. The lower reach of the chain returns or travels preferably between the floor 60 and the bottom plate or plates 2 of the machine.

Idler sprockets 82 may be employed in front of the sprocket wheels 66 and 68 to keep the chain on the floor 60. In Fig. 3 the floor 60 at its rear end is shown slightly raised and the sprocket wheels or rollers 80 and 81 are located at the point of change of inclination of the parts of floor 60 and are utilized to keep the chains 63 and 64 in position on the parts of the floor which are of different inclination. In Figs. 17 to 19 the arms 73 for blades 70 are shown on the inside of the sprocket chains so as to pass rollers 80 and 81.

The embodied form of means for driving the conveying mechanism in its reciprocatory movement, is driven from the motor 50 and includes a suitable form of automatic reversing mechanism. As embodied, a bevel gear wheel 91 is fixed on shaft 54, and meshing therewith is a beveled gear wheel 92, which is fixed on a shaft 93, journaled in bearings 94 and 95. Fixed on shaft 93 is a gear wheel 96, with which meshes a gear wheel 97, mounted loosely on a shaft 98. Shaft 98 is journaled in bearings 99 and 100 on the machine frame. The gear wheel 97 is provided with a clutch member 101.

Fixed also on shaft 93 is a gear wheel 102, which meshes with an idler gear wheel 103, mounted on a stub shaft journaled in a bearing 104 on the machine frame. Idler gear wheel 103 meshes with a gear wheel 105, which is mounted loosely on shaft 98 similarly to gear wheel 97, but owing to idler gear 103, gear wheels 97 and 105 rotate in opposite directions. Gear wheel 105 is provided with a clutch member 106.

Mounted upon shaft 98 to rotate therewith, but slidable therealong, is a double clutch member 107, adapted to pass alternatively into engagement with clutch member 101 or with clutch member 106, thereby imparting rotation to the shaft 98 either in one direction from gear wheel 97 or in the other direction from gear wheel 105. The clutch member 107 is thrown out of engagement with one of the clutch members 101 and 106 and into engagement with the other thereof in alternation by means of mechanism later to be described and thereby automatically reverses the direction of travel of the conveyor mechanism.

The further driving connections for the main conveyor comprise a beveled gear wheel 110 fixed on shaft 98, and meshing therewith a beveled gear wheel 111, fixed 5 on a shaft 112, which is journaled at 113 and 114 in the machine frame, and extends across the conveyor beneath floor 60. Sprocket wheels 115 and 116 are in mesh with the chains 64 and 63, respectively, to 10 impart the required reciprocatory movement thereto and to the conveyor blades 70.

The cross conveyor shown at the upper right hand end of Fig. 1 is similar in its construction and manner of operation, but 15 is shown with only one conveyor blade 70. This conveyor blade is connected at its ends, in the manner already described, to chains 120 and 121, which run over sprocket wheels 122 and 123, and 124 and 125, respectively. Sprocket wheels 123 and 125 are both fixed on a shaft 126, journaled at 20 127 and 128 in the machine frame, this construction causing the chains 120 and 121 to travel together. Fixed on shaft 98 is 25 a gear wheel 129, which meshes with gear wheel 130, which is fixed on the shaft of sprocket wheel 122. Thus the short conveyor is reciprocated to and fro in the same manner as the long or main conveyor.

30 Referring now to the means for automatically throwing clutch 107 to reverse the direction of travel of the conveyors, this mechanism is shown partly in Fig. 1 and in detail in Fig. 11. The clutch member 107 is provided with an annular groove 136, into which projects a pin 137 which is fixed 35 on an arm 138. Arm 138 is loosely pivoted on a bearing pin 139, and fixed to the arm 138 is an arm 140, provided with lugs 141 40 and 142. Pivottally mounted also on pin 139 is an arm 143, which will engage with lugs 141 or 142 to move clutch member 107 in one direction or the other, which is 45 preferably bent downwardly so that the free end thereof is in the path of two spaced apart lugs 144 and 145 fixed on the lower reach of the chain 120.

A tension spring 146 has one end 147 thereof fixed to the arm 143 and the other 50 end thereof fixed to the machine frame, the spring 146 being in position to snap or impel the arm 143 in either direction when it has once passed over the dead center. Thus, when in the position of Fig. 11, the 55 lug 145 will engage the arm 143 and will push it, thereby beginning to disengage the clutch member 107 from the clutch member 106. When arm 143 has just passed the 60 dead center for the spring 146, the spring will snap it in the opposite direction, and will thus throw the clutch member 107 into engagement with the clutch member 101 and thereby reverse the direction of travel of the conveyors. This mechanism prevents 65 the clutch member 107 stopping in neutral

position, which would stop the conveyor mechanism. The operation is just the reverse on the opposite travel of chains 120. When the short conveyor is not used, chain 120 can be left to operate clutch 107 or the 70 mechanism can be turned about and operated from chain 64 as shown in Fig. 16. The distance of travel of the blades 70 relatively to the length of the machine may be varied, if desired. By putting arm 143 on 75 the dead center of spring 146, or by unhooking spring 146 at either end, the conveying mechanism can be stopped. By moving one of the lugs 144 or 145 toward or away from the other, the stroke or reciprocatory travel of the conveyor blades 70 may 80 be lengthened or shortened as desired.

The embodied form of means for advancing the machine, and thereby pressing the cutter chain to the work, comprises winding cables having one end anchored to screw jacks or other suitable anchorages, placed 85 in proper position, and which are wound up on drums driven from the motor 50. The means for accomplishing this is shown 90 rather diagrammatically in the drawings, it being understood that in actual working conditions, suitable gearing may be provided for effecting the desired feeding movement in relation to the speed of the cutting 95 operation. As embodied, the motor shaft has fixed thereon a bevel gear 154, with which meshes, respectively, two bevel gear wheels 155 and 156, which are loosely mounted on the shaft 157, this shaft being journaled in bearings 158 and 159, mounted on the machine frame. Fixed on the shaft 157 are drums 160 and 161. Mounted on shaft 156 to rotate therewith, but slidably 100 therealong, is a clutch 162, adapted to engage with either the gear wheel 155 or the gear wheel 156 to rotate the drums 160 and 161 in either direction. This clutch 105 may be manually operated in a known or suitable manner.

In Fig. 15 the machine is shown, somewhat diagrammatically, operating to drive a heading or entry, with cables 165 and 166 being wound on the drums 160 and 161, and having their ends anchored to 115 screw jacks 167 and 168 fastened in any convenient place in the mine wall or roof. Any suitable sheaves for guiding the cables in a well known manner may be employed 120 if desired, such for instance as the sheaves 165' and 166'.

The invention in its broader aspects is not limited to the specific mechanisms shown and described but departures may be made therefrom within the scope of the accompanying claims without departing from the principles of the invention and without 125 sacrificing its chief advantages.

What I claim is:—

1. A mining machine including in com- 130

hination, a flat, low machine frame constructed and arranged to be propelled on the ground, an endless guideway structure rigidly and permanently mounted at the front of said frame, a cutter chain running in said guideway, means for driving said chain, and for driving the frame along the ground to press the cutter chain into the work, said guideway and cutter chain being constructed and arranged to cut an endless kerf, the exterior boundaries of which are at least co-extensive with the maximum cross-sectional area of the machine.

2. A mining machine including in combination, a flat, low machine frame constructed and arranged to be propelled along the ground, an upstanding guideway mounted at the front of said frame, a cutter chain running in said guideway, means for driving said chain and for driving the frame along the ground to press the cutter chain into the work, said frame having an upstanding prime mover at its rear and located at one side of the center of said frame for actuating said driving means, and conveying means co-extensive with the front of said frame, said means being constructed and arranged to transport said coal rearwardly and to one side of said upstanding prime mover.

3. A mining machine including in combination, a low machine frame having a flat upper surface portion, said frame being constructed and arranged to be propelled along the ground, an upstanding, endless guideway mounted at the front of said frame, a cutter chain running in said guideway, means for driving said chain and for driving the frame along the ground, including upstanding mechanism located on and occupying a limited portion of the rear upper surface of said frame, and conveying means substantially co-extensive with the flat upper surface of said frame, said means being constructed and arranged to transport the coal rearwardly and laterally of said upstanding mechanism.

4. A mining machine including in combination, a low, machine frame constructed and arranged to be propelled on the ground, an upstanding endless guideway mounted on the front of said frame, a cutter chain running in said guideway, means for driving the chain and for driving said frame along the ground, said frame having a flat portion lying in a single horizontal plane and extending from the cutting front to the rear thereof, said flat portion being constructed and arranged to convey the coal backwardly to the rear of the frame.

5. A mining machine including in combination a flat, low machine frame, a vertically disposed endless cutter chain guideway in fixed position on the frame, and having

top and bottom horizontal reaches and side vertical reaches, a cutter chain running in the guideway, means for driving the cutter chain, and means for advancing the machine frame to press the cutter chain into the work.

6. A mining machine including in combination a flat, low machine frame, a vertically disposed endless cutter chain guideway mounted across and at the front of the frame, and having top and bottom horizontal reaches and side vertical reaches, a cutter chain running in the guideway, means for driving the cutter chain, and means for advancing the machine frame to press the cutter chain into the work.

7. A mining machine including in combination a flat, low machine frame, a vertically disposed endless cutter chain guideway in fixed position on the frame, and having top and bottom horizontal reaches and side vertical reaches, the entire space within the cutter chain guideway being clear, a cutter chain running in the guideway, means for driving the cutter chain, and means for advancing the machine frame to press the cutter chain into the work.

8. A mining machine including in combination a flat, low machine frame, a vertically disposed endless cutter chain guideway mounted across and at the front of the frame, and having top and bottom horizontal reaches and side vertical reaches, the entire space within the cutter chain guideway being clear, a cutter chain running in the guideway, means for driving the cutter chain, and means for advancing the machine frame to press the cutter chain into the work.

9. A mining machine including in combination a flat, low machine frame, a vertically disposed endless cutter chain guideway mounted across and at the front of the frame, and at least equal in width to the machine frame, and having top and bottom horizontal reaches and side vertical reaches, a cutter chain running in the guideway, means for driving the cutter chain, and means for advancing the machine frame to press the cutter chain into the work.

10. A mining machine including in combination a flat, low machine frame, a vertically disposed endless cutter chain guideway mounted across and at the front of the frame, and having top and bottom horizontal reaches and side vertical reaches, a cutter chain running in the guideway, means for driving the cutter chain, a conveyor within the machine frame and extending from the bottom of the cutter chain guideway to the rear of the machine, and means for advancing the machine frame to press the cutter chain into the work.

11. A mining machine including in combination a flat, low machine frame, a vertically disposed endless cutter chain guideway

- mounted across and at the front of the frame, and having top and bottom horizontal reaches and side vertical reaches, a cutter chain running in the guideway, means for driving the cutter chain, a conveyor within the machine frame and extending throughout along the bottom of the machine from the bottom of the cutter chain guideway to the rear of the machine, and means for advancing the machine frame to press the cutter chain into the work.
12. A mining machine including in combination a flat, low machine frame, a vertically disposed endless cutter chain guideway in fixed position on the frame, and having top and bottom horizontal reaches and side vertical reaches, a cutter chain running in the guideway, means for driving the cutter chain, braces between the machine frame and the vertical reaches of the cutter chain guideway adapted to pass into the vertical parts of the kerf as the machine advances, and means for advancing the machine frame to press the cutter chain into the work.
13. A mining machine including in combination a flat, low machine frame, a vertically disposed endless cutter chain guideway mounted across and at the front of the frame, and having top and bottom horizontal reaches and side vertical reaches, a cutter chain running in the guideway, means for driving the cutter chain, braces between the machine frame and the vertical reaches of the cutter chain guideway adapted to pass into the vertical parts of the kerf as the machine advances, and means for advancing the machine frame to press the cutter chain into the work.
14. A mining machine including in combination a flat, low machine frame, a vertically disposed endless cutter chain guideway mounted across and at the front of the frame, and having top and bottom horizontal reaches and side vertical reaches, the entire space within the cutter chain guideway being clear, a cutter chain running in the guideway, means for driving the cutter chain, braces between the machine frame and the vertical reaches of the cutter chain guideway adapted to pass into the vertical parts of the kerf as the machine advances, and means for advancing the machine frame to press the cutter chain into the work.
15. A mining machine including in combination a flat, low machine frame, a vertically disposed endless cutter chain guideway in fixed position on the frame, and having top and bottom horizontal reaches and side vertical reaches, a cutter chain running in the guideway, means for driving the cutter chain, means for advancing the machine frame to press the cutter chain into the work, and a low, flat, horizontally disposed conveyor within the machine frame, extending

from just behind the cutter chain guideway to the rear of the frame and entering the bottom horizontal reach of the kerf as the machine advances.

16. A mining machine including in combination a flat, low machine frame, a vertically disposed endless cutter chain guideway mounted across and at the front of the frame, and having top and bottom horizontal reaches and side vertical reaches, a cutter chain running in the guideway, means for driving the cutter chain, means for advancing the machine frame to press the cutter chain into the work, and a low, flat, horizontally disposed conveyor within the machine frame, extending from just behind the cutter chain guideway to the rear of the frame and entering the bottom horizontal reach of the kerf as the machine advances.

17. A mining machine including in combination a flat, low machine frame, a vertically disposed endless cutter chain guideway mounted across and at the front of the frame, and having top and bottom horizontal reaches and side vertical reaches, the entire space within the cutter chain guideway being clear, a cutter chain running in the guideway, means for driving the cutter chain, means for advancing the machine frame to press the cutter chain into the work, and a low, flat, horizontally disposed conveyor within the machine frame, extending from just behind the cutter chain guideway to the rear of the frame and entering the bottom horizontal reach of the kerf as the machine advances.

18. A mining machine including in combination a flat, low machine frame, a vertically disposed endless cutter chain guideway in fixed position on the frame, and having top and bottom horizontal reaches and side vertical reaches, a cutter chain running in the guideway, means for driving the cutter chain, means for advancing the machine frame to press the cutter chain into the work, and a horizontally disposed conveyor having traveling conveying blades adapted to lie down to enter the bottom horizontal reach of the kerf as the machine advances and to stand up to convey away the dislodged coal.

19. A mining machine including in combination a flat, low machine frame, a vertically disposed endless cutter chain guideway in fixed position on the frame, and having top and bottom horizontal reaches and side vertical reaches, a cutter chain running in the guideway, means for driving the cutter chain, means for advancing the machine frame to press the cutter chain into the work, and a horizontally disposed conveyor, located within the machine frame and extending from just behind the cutter chain guideway to the rear of the machine, and having traveling conveying blades adapted to lie

down to enter the bottom horizontal reach of the kerf as the machine advances and to stand up to convey away the dislodged coal.

20. A mining machine including in combination of flat, low machine frame, a vertically disposed endless cutter chain guideway mounted across and at the front of the frame, and having top and bottom horizontal reaches and side vertical reaches, a cutter chain running in the guideway, means for driving the cutter chain, means for advancing the machine frame to press the cutter chain into the work, and a horizontally disposed conveyor having traveling conveying blades adapted to lie down to enter the bottom horizontal reach of the kerf as the machine advances and to stand up to convey away the dislodged coal.
21. A mining machine including in combination a flat, low machine frame, a vertically disposed endless cutter chain guideway mounted across and at the front of the frame, and having top and bottom horizontal reaches and side vertical reaches, a cutter chain running in the guideway, means for driving the cutter chain, means for advancing the machine frame to press the cutter chain into the work, and a horizontally disposed conveyor, located within the machine frame and extending from just behind the cutter chain guideway to the rear of the machine, and having traveling conveying blades adapted to lie down to enter the bottom horizontal reach of the kerf as the machine advances and to stand up to convey away the dislodged coal.

22. A mining machine including in combination kerf cutting mechanism including a cutter chain and another chain running in engagement with and driving the cutter chain.

23. A mining machine including in combination kerf cutting mechanism including a cutter chain guideway, a cutter chain running in the guideway, and another chain running within the guideway in engagement with and driving the cutter chain.

24. A mining machine including in combination kerf cutting mechanism including a cutter chain and another chain running in engagement with and driving the cutter chain, a motor, and connections therefrom to said driving chain.

25. A mining machine including in combination kerf cutting mechanism including a cutter chain guideway, a cutter chain running in the guideway, another chain running within the guideway in engagement with and driving the cutter chain, a motor, and connections therefrom to said driving chain.

26. A mining machine including in combination kerf cutting mechanism including a cutter chain and another chain running in engagement with the cutter chain for a por-

tion only of its length and driving the cutter chain.

27. A mining machine including in combination kerf cutting mechanism including a cutter chain guideway, a cutter chain running in the guideway, and another chain running within the guideway in engagement with the cutter chain for a portion only of its length and driving the cutter chain. 75

28. A mining machine including in combination kerf cutting mechanism including an endless cutter chain and guideway having a plurality of reaches angularly disposed with respect to each other and a driving chain running within the guideway and in driving engagement with the cutter chain in one of said reaches. 80

29. A mining machine including in combination kerf cutting mechanism including an endless cutter chain and guideway having a plurality of reaches angularly disposed with respect to each other and a driving chain running within the guideway and in driving engagement with the cutter chain in one of said reaches, said driving chain extending outside the guideway, a motor, and driving connections from the motor for said driving chain and engaging therewith outside said guideway. 85

30. A mining machine including in combination kerf cutting means including an endless cutter chain and guideway therefor having vertical and horizontal reaches, a driving chain in driving engagement with the cutter chain and extending backwardly therefrom along the machine in position to enter a vertical reach of the kerf, a motor at the rear of the machine, and driving connections between the motor and the driving chain. 100

31. A mining machine including in combination kerf cutting means including an endless cutter chain and guideway therefor, a driving chain in driving engagement with the cutter chain and extending backwardly therefrom along the machine in position to enter the kerf, a motor at the rear of the machine, and driving connections between the motor and the driving chain. 115

32. A mining machine including in combination a machine frame, a vertically disposed endless cutter chain guideway in fixed position upon, and extending across the frame at the front end thereof, a motor on the frame at one of the rear corners thereof, driving connection from the motor to the cutter chain, and a conveyor extending along the frame from just in the rear of the cutter chain guideway past the motor to the rear of the machine. 120

In testimony whereof, I have signed my name to this specification.

RICHARD PEALE.
